UNITED STATES PATENT OFFICE.

HALVOR ANDRESEN, OF NEW YORK, N. Y., ASSIGNOR TO THE VACUUM MUFFLER CORPORATION, OF NEW YORK, N. Y., A CORPORATION OF NEW YORK.

MUFFLER.

1,361,662.

Specification of Letters Patent. Patented Dec. 7, 1920.

Application filed October 22, 1917. Serial No. 197,812.

To all whom it may concern:

Be it known that I, HALVOR ANDRESEN, a subject of the King of Norway, and a resident of the borough of Manhattan, in the city of New York, county and State of New York, have invented new and useful Improvements in Mufflers, of which the following is a specification.

The invention relates to mufflers for use with internal combustion engines or in fact with any engine or device that has an intermittent discharge into an atmosphere having a lower pressure than that of said discharge.

The muffler to which the invention is directed is constructed so that the gases from the muffler inlet first enter an initial receiving space that is located within a central portion of the muffler casing and so that the gases passing from this initial receiving space or central chamber will flow between outwardly extending deflecting plates, which may be considered as guiding members, into a conducting chamber through which the 25 gases flow toward the muffler discharge or exhaust opening. The muffler has spaced heads, one at each end of the muffler and the deflecting plates or members are located between said heads. A part of the deflecting 30 plates or members are preferably carried by one head and the rest of the deflecting plates or members are preferably carried by the other head.

According to the present invention there is located upon the head opposite the intake a removable conical member the vertex of which extends into the initial receiving space or central chamber of the muffler. The function of this conical member is to deflect 40 gases, as they enter said initial receiving space or chamber, into the passageways defined between adjacent deflecting plates. This conical member is preferably held in place on the head which carries it by the 45 deflecting plates carried on the companion head, as will hereinafter more fully appear.

The invention is also directed to other features of construction as will hereinafter more fully appear and which are clearly 50 brought out in the claims.

As illustrating a specific embodiment of the invention reference is made to the accompanying drawing which forms a part of this specification and in which drawing,

55 Figure 1 is a vertical longitudinal sec-

tional view of the muffler and is a view taken as on the plane indicated by the line 1—1 of Fig. 2.

Fig. 2 is a vertical cross-sectional view taken as on the line 2—2 of Fig. 1 looking in the direction of the arrows.

Fig. 3 is a partial sectional view taken as on the line 3—3 of Fig. 2 looking in the direction of the arrows.

Fig. 4 is a partial vertical longitudinal 35 sectional view showing a modified construction; and

Fig. 5 is a partial vertical cross-sectional view showing another modified construction.

The muffler comprises a suitable casing 70 which may be considered as having spaced heads A and B and side wall C. The head A may be arbitrarily referred to as the rear head of the muffler and the head B as the forward head since the gases from the muffler inlet first pass through the rear head A and flow forwardly toward and finally through the forward head B. This nomenclature, however, it will be understood is as above indicated merely an arbitrary one 75 adopted for convenience. The side wall may be considered to start at 1, continue along the curved path to 2, 3, 4, 5, finally returning to 1, thereby forming an inclosed exterior curved side wall. The major portion 80 of this side wall, to wit, the part defined by 1, 2, 3 and 4, is part of a cylinder having its center at X while the minor portion of the side wall, to wit, the part defined by 4, 5, 1, is part of a cylinder having 85 its center at Y. The curved side wall C can be formed partially on the rear head A, for instance portion ca, and partially on the forward head B, for instance portion cb. It will readily be appreciated, however, 90 that the side wall C can be an independent member placed between the opposing heads A and B. In the construction shown the side wall portion ca is provided with a rib cc which enters a groove cd in the side wall 100 portion cb.

The rear head A is provided with a tubular projection D to which an exhaust pipe D' of a hydrocarbon or other engine may be connected. The incoming gases which are 105 discharged from the engine flow through an inlet opening IN into the initial receiving space or central chamber E which, as the name implies, is located within a central portion of the muffler casing. The forward 110

end of this initial receiving space or central chamber E is defined by a conical portion or member F which extends rearwardly from the forward head B so that the apex f 5 of the cone extends into the initial receiving space or central chamber E. The coned portion of this member F serves to turn or deflect laterally the incoming gases which are traveling forward in a longitudinal direction from the inlet opening. This turning or deflecting of the incoming gases is more or less gradual due to the conical member F the surface of which is in the form of a smooth curve, as will appear from the 10 cross-section shown in Fig. 1 of the drawing.

The sides or peripheral portions of the initial receiving space or central chamber E are defined by the inner ends g and g' of the series of deflecting plates or members G and 20 G'. The ends g—the end g' being an exception—are arranged along a circle having its center at o and therefore the initial receiving space is substantially a cylindrical space having an entrant cone at one end. 25 The plates G are carried on the rear head A and extend forwardly adjacent to the inner faces of the forward head B, while the plates G' are carried by the forward head B and extend rearwardly adjacent to the rear head A. 30 These deflecting plates G and G' are arranged in such a manner that alternate plates are carried by each head and so that there is a narrow entrance space, as at es, between adjacent plates when all the plates are in assembled position.

The outer ends of the deflecting plates are preferably arranged along a circular path the center of which circle is located at Z. The space S between the outer ends of 40 these deflecting plates on the one hand and the side wall C on the other, and between the rear head A on the one hand and the forward head E on the other, constitutes the conducting chamber through which the gases 45 flow on their way from between the deflecting plates to the discharge opening D0 of the muffler. This discharge opening D0 extends through a tubular projection H. A pipe K may be positioned in the discharge 50 opening in this tubular projection H, as will be seen in Fig. 3. In order that the pipe K will not extend too far into the muffler there is provided a stop k which extends forwardly from the rear head A. The heads 55 A and B are secured together by bolts L which extend from one head to the other.

In order to facilitate the manufacture of this device the conical member F is made as a separate member having a forwardly extending flange or shoulder M that enters an opening N in the head B. It also has a laterally extending flange portion P that overlaps the head B thus making a relatively tight joint between the member F and the 60 head B. The member F has three radial 65

arms R engaged by the ends R' of three of the deflecting plates so that when the parts of the muffler are in assembled position said conical member F will be clamped in position between the rear side of the forward head B and the forward end of three deflecting plates that are carried on the rear head A. The apex of the conical member F is concentric with the center line of the intake opening IN and of the center o of the circle about which the inner ends g of the deflecting plates G and G' are located. The end g' of one of the deflecting plates extends inwardly past this circle and this extending end g' serves two functions; firstly, 70 to enter a cut out on the conical member so that the latter can be assembled in only one position and, secondly, to provide a stop at its rear end to limit the distance that the pipe D' can enter the inlet opening of the 75 muffler; in other words, so that the pipe cannot be positioned too far in the muffler.

In Fig. 4 a construction is shown in which the conical member F'—which corresponds 80 in its function to the conical member F previously described—is held in place by screw-threads and is readily insertible in place or removable from its position in the muffler, as will be manifest from an inspection of said Fig. 4.

In Fig. 5 there is illustrated a modified construction in which the vanes or deflecting plates are curved. These vanes resemble in many respects the construction which is shown in my co-pending application Serial No. 177,067 which was filed June 26th, 1917. The narrow entrance space between the deflecting plates is designated as es and corresponds to the narrow entrance space es of the construction shown in Fig. 2. The 100 width of the narrow slots or entrance spaces es can be made from one (1) millimeter down to about three-tenths ($\frac{3}{10}$) of a millimeter, dependent upon the form and length of the deflecting plates. The long or 105 curved deflecting plates would allow the wider slots while the shorter or straight plates preferably have the narrow slots to maintain the muffling effect, and the greater 110 length of the plates between which the 115 gases must pass and the greater the length from the narrow slots to the delivery opening of the muffler the wider the slots may be made.

In constructing mufflers it is quite important that the ratio by which the space between the deflecting plates widen must not exceed a certain limit in order to keep the gas flow as uniform as possible. The narrow slots between the deflecting plates can 120 be made relatively long as desired. The longer the slots, however, the greater the increase in the weight and cost of the muffler and the length of the slots ought to be made so that the combined free cross-sectional area 130

- of the slots is equal to a certain minimum which can be figured out when the conditions of the gas and piston displacement are known. This combined cross-sectional area 5 will generally figure out to be about the same as the free exhaust valve area of the engine or a little less.
- In the operation of the muffler the gases discharged from the hydrocarbon engine 10 flow in a longitudinal direction through the inlet opening IN of the rear head A. The coned portion of the conical member F then assists in deflecting the gases laterally into the numerous narrow entrance spaces or 15 slots es provided between the adjacent inner ends of the deflecting plates or members G, G'. As the gases flow through said narrow spaces they are allowed to gradually expand finally entering the conducting chamber 20 space S through which the gases flow, as in the direction indicated by the arrows s, to the discharge opening DO through which the gases finally pass on their way from the muffler.
- 25 In assembling the muffler the conical member F is first placed in proper position on the forward head B; thereafter the rear head A is brought into position and clamped by the bolts (or rivets) at L.
- 30 When the heads are clamped in position by the bolts the forward ends of three of the deflecting members or plates G engage the rear side of the ribs or projections R on the conical member F so that the conical mem- 35 ber is firmly clamped in place and so that there is a tight joint between the flanged portions of the conical member F and that portion of the head B which defines the opening N.
- 40 The longitudinal center line of the inlet opening passes through the center o of the circle about which the inner ends of the deflecting plates G and G' are arranged and also through the apex of the coned portion 45 of the conical member F. The center Z of the circle along which the outer ends of the deflecting plates are arranged is eccentric with the center X of the large cylindrical portion of the side wall casing and both of 50 these centers are eccentric with the center o previously referred to. These three centers o, Z and X are, however, arranged substantially along the same line.
- The deflecting plates or members which 55 are farthest from the discharge opening DO are the shortest while the deflecting plates nearest the discharge opening are the longest and the plates or members between these short and long plates gradually in- 60 crease in length. It will be observed that the gases which have the longest distances to travel in the conducting chamber space S have the shortest distance to travel when passing between adjacent deflecting plates 65 or members; while on the other hand those

gases which have little or no travel along the conducting chamber space S have the longest distance to travel between the adjacent plates or members.

The result of this construction is a relatively uniform flow of gases from the initial receiving space or central chamber to the discharge opening and the intermittent impulses or bursts which enter the receiving space are therefore ironed out so that there 75 is a relatively uniform discharge from the discharge opening DO.

The improvements herein set forth are not limited to the precise construction and arrangement shown and described for they 80 may be embodied in various forms and modifications without departing from the spirit and scope of the invention.

What I claim is:

1. In a muffler, the combination of a cas- 85 ing comprising a cylindrical side wall and spaced heads, one of said heads having an inlet opening therein, the other head having a discharge opening therein, a plurality of spaced deflecting plates or members radially arranged within said casings and about said inlet opening to form an initial receiving space, and a conical member removably secured to one of said heads and projecting into said initial receiving space. 95

2. In a muffler, the combination of a cas- 100 ing comprising spaced heads and a side wall, one of said heads having an inlet opening therein, the other head having a discharge opening therein, a conical member remov- 105 ably secured to last mentioned head and arranged with an apex of said conical member opposite said inlet opening, and a plurality of spaced deflecting plates or mem- 110 bers radially arranged within said casing around said conical member, the inner ends of said deflecting plates defining an initial receiving space.

3. A muffler of the class described having spaced heads one of which has an inlet 115 opening therein through which incoming gases pass, a removable conical member seated on the opposing head, spaced deflecting plates or members each extending from one head to the other, and means for securing said heads in proper position relative to each other, the conical member being clamped in place between and by said deflecting plates on one hand and the head upon which it is seated on the other. 120

4. A muffler of the class described comprising in combination a rear head having a rearwardly extending tubular projection that provides the inlet opening of the muffler, a forward head having an opening therein in 125 which opening there extends and upon which forward end there is seated a conical member, the apex of the coned portion of which conical member is located opposite the muffler inlet opening, a series of deflecting plates 130

or members arranged to define the peripheral portion of an initial receiving space, into which receiving space incoming gases pass and from which space the gases flow into narrow slots provided between said deflecting plates or members, some of the deflecting plates or members being carried on the rear head and being constructed so as to engage said conical member in a manner to clamp said conical member in position between them and the forward head when the heads are secured in proper position relative to each other.

5. In a muffler, the combination of a casing comprising a cylindrical side wall and two circular heads, one of said heads having a circular opening eccentrically located therein, the other head having a circular discharge opening located near its periphery, and a plurality of spaced deflecting plates or members arranged within said casing, the inner ends of said plates being arranged around the inlet opening to form an initial receiving space, while the other ends 20 are arranged in a circle, the center of which is located between the centers of the inlet and discharge openings.

6. In a muffler, the combination of a casing comprising a cylindrical side wall and two circular heads, one of said heads having an inlet opening eccentrically located therein, the other head having a discharge opening located near its periphery, and a plurality of deflecting plates or members 30 radially arranged within said casing so that the inner ends of said plates will form about said inlet opening a circular receiving space

while the outer ends will define a circle, the circles defined by the inner and outer ends of said deflecting plates being eccentric with relation to each other and with said side wall.

7. In a muffler, the combination of a casing comprising a cylindrical side wall and two circular heads, one of said heads having an inlet opening eccentrically located therein, the other head having a discharge opening eccentrically located therein, and a plurality of spaced deflecting plates or members radially arranged within said casing 40 and about said inlet opening so as to form an initial receiving space, the inner ends of adjacent deflecting plates or members being $\frac{1}{16}$ to 1 millimeter apart.

8. In a muffler, the combination of a casing comprising a cylindrical side wall and spaced heads, one of said heads having an inlet opening eccentrically located therein, the other head having a discharge opening eccentrically located therein, and a plurality of deflecting members radially arranged within said casing so that the inner ends thereof will form an initial receiving space about said inlet opening, said members being suitably spaced so that substantially all 55 of the exhaust gases will be brought into contact with and cooled by said members and guided toward said casing.

The specification signed and witnessed this 18th day of October, A. D. 1917.

HALVOR ANDRESEN.
